UNITED STATES PATENT OFFICE

107,062

DESIGN FOR A COMBINED SECTIONAL LUGGAGE RACK AND LIGHTING FIXTURE UNITS

Albert L. Arenberg, Highland Park, Ill., assignor to Patent License Corporation, Chicago, Ill., a corporation of Illinois

Application February 13, 1937, Serial No. 67,632

Term of patent 14 years

To all whom it may concern:

Be it known that I, Albert L. Arenberg, a citizen of the United States, residing at Highland Park, in the county of Lake and State of Illinois, have invented a new, original, and ornamental Design for a Combined Sectional Luggage Rack and Lighting Fixture Units, of which the following is a specification, reference being had to the accompanying drawing, forming a part thereof.

In the drawing:

Fig. 1 is a fragmentary perspective view of a

combined sectional luggage rack and lighting fixture units, showing my new design;

Fig. 2 is a bottom plan view of the same;

Fig. 3 is a transverse sectional view, taken on the line 3—3 of Fig. 2, and

Fig. 4 is a top plan view thereof.

I claim:

The ornamental design for a combined sectional luggage rack and lighting fixture units, substantially as shown.

ALBERT L. ARENBERG.
